UNITED STATES PATENT OFFICE.

EDWARD H. CRONINGER, OF COVINGTON, KENTUCKY.

DESIGN FOR A BAR-PIN.

SPECIFICATION forming part of Design No. 22,073, dated December 20, 1892.

Application filed November 14, 1892. Serial No. 452,003. Term of patent 14 years.

To all whom it may concern:

Be it known that I, EDWARD H. CRONINGER, a citizen of the United States, residing at Covington, in the county of Kenton and State of Kentucky, have invented a new and original Design for a Bar-Pin, of which the following is a specification.

The particular and also the general features of the device are illustrated in the accompanying drawing, in which 1 designates the body of the bar which is mainly oblong in form, having on the left a circular enlargement 2, on the face of which is represented a series of spokes radiating from a common center and a tire which forms a rim or flange. The ends of the tire are united to the upper and lower projecting borders of the bar. These borders are scalloped or otherwise ornamented as described. On the right, the bar terminates in a compound scroll 3. A similar scroll 4, is at-

tached to the lower edge of the bar near the rim 2, and its end toward the center of the bar is looped or eyelet shaped. On the face of the bar are two bands 6 and 7 united at their lower ends, but flaring upward: the 25 left hand band does not extend upward to the part 2, but the right hand band crosses the rim of the wheel and terminates in a scroll 6, which overlies the upper border of the bar for a short distance.

3c

What I claim is:

The design for a bar pin as described and shown.

In testimony that I claim the foregoing I have hereunto set my hand, this 12th day of 35 October, 1892, in the presence of witnesses.

EDWARD H. CRONINGER.
